2 SHEETS-SHEET 2.

UNITED STATES PATENT OFFICE.

WILBURT WARD, OF MITCHELL, INDIANA.

KILN.

No. 906,174.

Specification of Letters Patent.

Patented Dec. 8, 1908.

Application filed April 8, 1908. Serial No. 424,926.

To all whom it may concern:

Be it known that I, WILBURT WARD, citizen of the United States, residing at Mitchell, in the county of Lawrence and State of Indiana, have invented certain new and useful Improvements in Kilns, of which the following is a specification.

My invention relates to certain new and useful improvements in furnace construction for kilns and the like, and the object of my invention is to produce a construction in which a high degree of heat can be maintained and which, by reason of the saving of heat produced and the prevention of radiation, will result in great economy in the fuel consumption.

With these and other objects in view my invention consists in certain constructions, combinations and arrangements of parts the preferred form of which will be first described in connection with the accompanying drawings and then the invention particularly pointed out in the appended claims.

Referring to the drawings wherein the same part is designated by the same reference numeral wherever it occurs, Figure 1 is a front view, partly broken away, of a furnace embodying my invention; Fig. 2 is a section taken on line 2, 2 of Fig. 1; Fig. 3 is a horizontal sectional view taken on line 3, 3 of Fig. 1; Fig. 4 is a detail perspective view of one of the sections comprising the brick arch for the furnace, and Fig. 5 is a detail sectional view taken through a pair of these arches, in order to show the connecting means between them.

1 designates the body of the furnace which, as shown, is built of brick and is rectangular in cross section, the body being provided with the ash pit 2, provided with the usual doors 3 and grate 4 extending across the upper portion thereof.

5 designates a series of arches which extend over the grate from one wall to the other. Preferably, and as shown, there are four of these arches used to cover the length of the furnace, as best shown in Fig. 2. The arches at the front and rear of the furnace are formed with a plain edge on their exterior edges, while the two interior arches and the edges of the outer arches adjacent to said interior arches are provided with the grooves 6 and the half round cut away portion 7 at the top of the arch. When these edges abut, as best shown in Fig. 2, a channel is formed having an opening extending thereinto at the

top of the arch. After the arches are assembled fire clay in the form of slush is poured into the grooves through the opening 7, whereby the joints between the arches are made tight and the structure solid.

8 designates partitions formed in any desired way, these partitions extending from alternate sides of the furnace and covering the joints between the arches 5.

9 is an inlet passage formed through the side wall of the furnace and preferably extending into the chamber between the side wall of the kiln, indicated at 10, and the partition 8 nearest the kiln.

11 is an outlet pipe extending into the chamber between the partition 8 nearest the front of the furnace and the front wall. This outlet extends down and is connected by means of a T-head 12, with a pipe 13 extending into the ash pit beneath the grate.

14 is a steam pipe extending into the T-head, whereby the T-head is formed into an injector nozzle and operates to draw air through the passage way on top of the arch 5 and force the same into the ash pit under pressure.

15 is a brick arch which extends over the top of the partitions 8 and completely covers the arch 5, whereby the tortuous passage 8 way between the partitions 8 is closed.

By the above construction it will be seen that the air supplied to the ash pit is heated by being passed over the top of the fire arches 5, and that this results in keeping the arches 5 cooler, which causes them to last longer in the operation of the furnace and also results in economy in fuel consumption.

I realize that considerable variation is possible in the details of construction and arrangement of parts without departing from the spirit of my invention, and I therefore do not intend to limit myself to the specific form shown and described.

I claim—

1. In a furnace for kilns, the combination with end and side walls, of an ash-pit, a grate extending over the ash-pit, an arch extending over the grate, a plurality of partitions extending over the top of the arch, said partitions extending alternately from the side walls of the furnace and forming a tortuous passage over the top thereof, a second arch extending over the top of the partitions, a connection between the end of the passage at the front of the furnace and the ash-pit whereby air may pass from the passage to the ash-pit, and one

of the side walls of the furnace being provided with an opening connected to the rear end of the passage.

2. In a furnace for kilns, the combination 5 with end and side walls, of an ash-pit, a grate extending over the ash-pit, an arch extending over the grate, a plurality of partitions extending over the top of the arch, said partitions extending alternately from the side 10 walls of the furnace and forming a tortuous passage over the top thereof, a second arch extending over the top of the partitions, a

pipe leading into the ash-pit, a pipe extending from the end of the passage at the front of the furnace, an injector connecting said pipes, and one of the side walls of the furnace being provided with an opening connected to the rear end of the passage. 15

In testimony whereof I affix my signature in presence of two witnesses.

WILBURT WARD.
